 Howard M. Cohn(57) **CLAIM**

The ornamental design for a sealing cover, as shown and described.

DESCRIPTION

FIG. 1 is a perspective view of a sealing cover showing my new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is an enlarged view of portion 9 shown in FIG. 2; and, FIG. 10 is an enlarged view of portion 10 shown in FIG. 8. The dot-dash broken lines represent boundaries of the enlarged portions and form no part of the claimed design.
